UNITED STATES PATENT OFFICE.

ROBERT GOULD JENNINGS, OF ELMIRA, NEW YORK.

JET DYEING APPARATUS AND PROCESS.

Application filed April 13, 1923. Serial No. 631,776.

This invention relates to a winding and dyeing apparatus, and more especially in some of its more specific details to a jet dyeing apparatus for dyeing textiles or the like.

It is a general object of the invention to provide an improved apparatus of the class mentioned which is effective and reliable in operation, simple in construction and comparatively inexpensive in production costs.

Another object is the provision of an improved winding and dyeing apparatus for random application of dye to yarn or the like in which the application of the dye is readily controllable, and being adapted for ready application to existing winding apparatus without much trouble and little rearrangement of parts.

Another object of the invention is the provision of an improved dyeing apparatus for applying dye to a traveling thread by projection of a jet or spray directly thereon.

Another object is to provide an improved process for the continuous or random application of dye to textiles whereby predetermined effects are readily obtainable.

Other objects will be in part obvious in connection with the following detailed description and in part pointed out in connection therewith.

The invention accordingly comprises the several steps and the relation and order of one or more of such steps with respect to each of the others, and the apparatus embodying features of construction, combinations of elements and arrangement of parts which are adapted to effect such steps, all as exemplified in the following detailed disclosure, and the scope of the application of which will be indicated in the claims.

For a more complete understanding of the nature and objects of the invention, reference is had to the following detailed description and to the accompanying drawings, in which,

Fig. 1 is a fragmentary side elevation of a winding unit equipped to the invention;

Fig. 2 is a fragmentary enlarged elevation of the swinging supporting frame, parts being shown in section for clearness of disclosure;

Fig. 3 is a horizontal sectional view showing a plan of the construction of Fig. 2;

Fig. 4 is a detailed fragmentary view of

the lever construction for holding the apparatus in operative position;

Fig. 5 is a horizontal section showing a plan view of the jet valve and controlling mechanism;

Fig. 6 is a central sectional view of the jet valve;

Fig. 7 is an elevation of the jet valve and operating means therefor, viewed at right angles from the position shown at Fig. 5;

Fig. 8 is a view similar to Fig. 7, but shows a modified form of the jet mechanism; and

Fig. 9 is a view similar to Fig. 7, but showing a still further modified form.

Referring now to the drawing for a detailed description of the embodiment of the invention there illustrated, a combined winding and dyeing unit is shown in Fig. 1, being provided with a supporting frame 10, carrying a rotatable spindle 11, adapted to carry a bobbin or support 12 rotatable with the spindle, and having a conical base 13. A vertically oscillatable member or rail 14 is supported by the frame 10, adjacent the spindle carrying a threaded upright rod 15, which carries a friction winding cup or nut 16 having a conical exterior surface for contact with the conical winding field 17 of the yarn or thread reposing on the bobbin. It is to be understood that the yarn, while being wound on to the bobbin, is distributed over the conical winding surface by the oscillating up and down movement of the rail 14, which moves over a vertical distance equal to the altitude of the conical surface. As the bobbin fills with yarn near the base thereof, the winding cup 16 will engage frictionally therewith, rotating it for upward adjustment on the threaded rod 15. In this manner the wound yarn presents a cylindrical surface at the base of the spindle, gradually increasing in altitude as the winding progresses, while the winding field 17 will remain conical throughout the winding operation, moving upwardly toward the top of the bobbin, until the winding is completed.

Furthermore, it will be understood that the traveling thread will be carried over the conical surface by the up and down movement of the rail 14. It will also be understood by those skilled in the art that this type of winding apparatus is capable of winding at a rapid rate, thus causing the

thread, both as it approaches the cone and in wound position on the cone, to travel at a rapid rate.

Any desired number of spindles such as above mentioned may be mounted in a series along the frame 10, and the rail 14 may be extended along this series of spindles carrying a threaded rod 15 for each spindle. As will be understood, all of the spindles with their winding mechanism may be operated together, forming a series of simultaneously operating winding units. The spindles are operated by a suitably driven mechanism, and the rail 14 is caused to oscillate up and down by a power driven cam mechanism, such as indicated diagrammatically at 18 in Fig. 1.

The dyeing apparatus is arranged in the embodiment shown to apply dye directly to the yarn after it has come to rest on the conical winding field of the bobbin, but may be arranged to apply the dye directly to the traveling thread A before it reaches the conical winding surface. This apparatus includes a swinging supporting guiding frame 19, forming a part of the winding mechanism, and having upper and lower spaced arms supported on the threaded rod 15. The lower arm is slidably connected to the rod 15 through a bushing 20 contacting with the threads, while the upper arm is connected through a sleeve 21 having a smooth interior surface contacting with the threads, the upper arm being rigidly secured to this sleeve. The sleeve is connected to the threads by a manually releasable spring pressed thread engaging member 22, as shown in Fig. 2, which may be released at will to permit vertical adjustment of the frame along the threaded rod. As shown in Fig. 2, the winding cup 16 is securely attached to the sleeve 21.

The swinging frame or bracket 19 carries a jet valve 23 normally lying adjacent the surface of the winding field of the bobbin, and in the embodiment shown in Figs. 2, 5 and 6 includes a stationary part 24 with a dye reservoir 25 and a conduit 26 leading thereto from a source of supply. A port 27 leads from the dye reservoir to the face of the stationary valve part, and a rotary valve part 28 is mounted tightly against the part 24 on a supporting pin 29 threaded into the stationary valve part, and at its opposite end into the upright member 30 of the swinging bracket. The rotary valve member is normally held in tightly mating position with respect to the stationary part by a spring 31 secured at one end to the rotary valve part and at its opposite end to a collar 32 fixed on the supporting pin 29. The rotary valve part is provided with a jet port 33, and the spring 31 not only holds the valve parts in mating position to provide a liquid tight joint, but also biases the rotary part so the valve ports

27 and 33 are out of alignment and the dye jet thus cut off. The jet port 33 may be shaped to form a jet or small concentrated stream of dye, which will be supplied to the dye valve under pressure, or it may be formed to atomize the dye passing therethrough so as to apply it to the textile in the form of a spray.

For operating the jet valve to open the same to flow dye as desired a mechanism is provided preferably controlled by the winding mechanism. In the embodiment shown, this operating mechanism includes a rotary friction wheel 34 carried by the swinging frame 19 and provided with a conical friction surface for frictional engagement with the conical winding field of the bobbin. This friction wheel carries a tappet 35 lying in position to engage at each revolution with the radial arms of a star wheel 36 supported on a stud 37 carried by the swinging frame. A ratchet wheel 38 is mounted to rotate with the star wheel, a spring detent 39 lying in position to engage the teeth of the ratchet wheel to prevent reverse rotation. A cam 40 is also carried by the star wheel lying in position to engage an arm 41 carried by the movable valve part 28. It will therefore be seen that as the friction wheel rotates, the cam will be brought successively into position to open, or partially open, the valve ports to provide an intermittent jet application of dye to the traveling textile. A pin 42 is fixed to the stationary valve part engaging in a slot 43 in the movable valve part to limit rotation thereof in either direction. This arrangement supports the operating arm 41 in proper position for engagement with the cam 40.

It will be noted that it will be necessary for the swinging frame 19 to swing on its vertical axis as it oscillates up and down during the winding operation in order that the friction wheel 34 may be always in frictional engagement with the conical winding field, and in order that the dye applicator may be always in proper position relative to the textile for efficient application of dye. Means for taking advantage of the tension of the running thread is provided for this purpose, including an inner lever arm 44 rigidly attached to the sleeve 21, and an outer lever arm 45 pivoted to the first arm, and carrying at its free end a guiding and supporting roller 46, lying normally in position to contact with an abutment post 47, which is long enough to extend over the normal vertical travel of the swinging frame. The outer lever arm has an upwardly extending lug 48 pivotally supported on which is a yarn supporting and guiding lever 49, having an angularly disposed arm 50 lying in position to contact with the lever arm 44. The arm lever 49 is supported upon the lug 48 by means of a screw having a spacing

sleeve 51, which may be replaced by a shorter or longer sleeve to increase or diminish at will the force transmitted to the swinging frame from the traveling yarn. The yarn supporting lever is provided with an extension 52 having a terminal loop supporting a yarn guiding member 53 of hard smooth material, such as porcelain, hard rubber, or hard wood. It will be seen that the yarn 5 tension will be transmitted from the thread A, through the yarn lever 49, and the lever arms 45 and 44 to the swinging frame, the post 47 acting as an abutment to receive the reactive force due to this action. Should 10 the thread break or become sufficiently slackened, the yarn lever 49 will be released to upward movement, and the lever arm 45 will then be permitted to swing around its pivotal connection with lever arm 44, thus 15 permitting the frame 19 to swing away from the bobbin; the intermittent application of dye is thus discontinued, until the apparatus 20 is reset.

The operation of the device is embodied 25 in the foregoing description. It is specially noted, however, that the rate of travel of the thread A will vary, reaching a maximum when winding at the base of the conical winding surface and a minimum when winding 30 at the apex thereof. However, due to the fact that the jet dye applicator is controlled directly from the conical winding field, it will be seen that the application of dye will be proportional to the rate of travel 35 of the thread throughout the winding operation, that is, the amount of dye applied per unit length of thread will be varied with the rate of travel of said thread. It will be observed that when the speed of the thread 40 varies, the speed of the cam 40 carried by the star wheel 36 also varies. Therefore, to take a specific instance, when the speed of the thread doubles, the speed of the cam also doubles, so that the frequency of the jets likewise doubles, and therefore the number 45 of jets per unit length of thread wound remains constant. The length of each patch or streak of dye applied to the thread also remains substantially constant or uniform, 50 since, although the jet valve remains open only approximately half as long at each valve opening, the speed of the thread is twice as great. Also since the rate of dye flow through the valve is substantially constant with a given dye pressure, it will be 55 seen that the amount of dye per unit length of thread wound will be only half as great; that is, the amount of dye applied per unit length of thread wound is less as the rate 60 of thread travel increases, or, in other words, the proportion of dye applied is less as the speed increases. It is in this sense that the term proportionately and similar expressions are employed in the claims. This variable 65 application of dye to the thread is effective

to produce the desirable mottled or variegated effect when knit into garments. It is also to be noted that the valve mechanism may be readily adjusted and controlled to a nicety, and desired effects thus obtained. 70 The dye being under pressure as stated, the jet is given a velocity whereby to cause the dye to strike the thread with some force so as to penetrate the fibers of the textile. Since the cam 40 is stopped and started very 75 abruptly by the operation of the tappet 35 upon the star wheel 36, and, moreover, since the cam 40 is provided with abrupt terminals, it will be seen that the valve is opened and closed with a quick action to 80 start or stop the jet very abruptly. Thus the dye is applied uniformly during the operation of the jet and dribbling is avoided at both the start and finish of jet operation. 85

In the modified form of the invention 90 illustrated in Fig. 8, the operating mechanism for the jet valve is similar to that previously described, being indicated by the same reference characters with exponents "a." In this case, however, the valve 23^a 95 itself is modified, the stationary part 24^a thereof having four pipes 54 leading thereto instead of only one as in the former case. Each of these pipes may lead to sources of different colored dye supply so jets of different colors may be projected upon the yarn. The movable part of the valve is provided with jet openings corresponding to the supply pipes 54, these openings being indicated in dotted lines in Fig. 8 at 55. These jet 100 openings are spaced similarly to the spacing of the pipes 54 and when the movable part of the valve is in normal or unoperated position as shown the jet openings are disaligned with respect to pipes 54 and flow of 105 dye cut off, but when the valve is operated, as when the cam 40^a engages the follower arm 41^a, the jet openings will be moved respectively to align with the pipes; in this manner jets of dyes of different color may be 110 projected simultaneously. It will be understood that the corresponding jets and pipes will be connected so the different colored dyes will not mingle in the operation of the 115 valve.

In the modification of the invention illustrated in Fig. 9, the operating parts for the valve, again, are similar to those disclosed in the first modification, being designated by the same reference numerals with exponents "b." The stationary part 24^b of the valve, however, is provided with four dye supply pipes 56, 57, 58 and 59 leading thereto, but a greater or lesser number may be employed if desired. These pipes may conduct dyes of different color to the jet valve as in the modification of Fig. 8. In this embodiment of the invention the cam 40^b is modified, having an elongated working face cooperating 125 with the follower arm 41^b in several dif- 130

ferent positions to hold the movable part of the valve temporarily in different positions. The movable part of the valve is provided with jet openings 60 and 61, the opening 60 being spaced from opening 61 slightly less than 180 degrees and lying, in unoperated or normal position of the valve, adjacent to the pipe 56, but slightly spaced therefrom to prevent flow of dye. In normal position of the valve the jet port 61 is spaced some distance from the pipe 58, but this spacing is greater than the spacing between port 60 and pipe 56 as will be obvious from the drawing.

In operation of the modified form of the invention of Fig. 9, the star wheel 36^b is given a step by step movement in a manner similar to that described above, the elongated cam face of cam 40^b engaging with the follower arm 41^b of the valve to move the latter step by step to different corresponding positions. In Fig. 9 the valve is shown in closed or normal position with the inclined part of the cam about to engage with the follower arm 41^b. The next succeeding step of the cam 40^b will move the jet port 60 into alignment with the pipe 56, permitting a jet of dye to be ejected. The next succeeding step of the cam moves jet port 60 out of alignment with pipe 56, closing it to a flow of dye, and at the same time moving port 61 into alignment with pipe 58, permitting dye to flow through jet port 61. At the third succeeding step port 60 moves into alignment with pipe 57, and port 61 out of alignment with pipe 58; while at the fourth succeeding step jet port 61 moves into alignment with pipe 59, while port 60 passes beyond pipe 57, cutting off dye flow therefrom. It will therefore be seen that the jet ports 60 and 61 will be opened to flow of dyes of different color therefrom, alternately and successively at the different steps of movement of the operating cam 40^b. At the fifth step of operation of the mechanism, following the fourth step as described, the follower arm 40^b passes beyond the inclined cam surface, and the valve is automatically moved again to initial position as shown in Fig. 9 under influence of the operating spring 31.

The embodiment of the invention shown in Fig. 9 provides for four different colors of dyes to be projected in successive jets, but there may be more or less than four pipes and the jet ports may be correspondingly arranged.

Since certain changes in carrying out the above process and in the constructions set forth, which embody the invention may be made without departing from its scope, it is intended that all matter contained in the above description or shown in the accompanying drawing shall be interpreted as illustrative and not in a limiting sense.

It is also to be understood that the following claims are intended to cover all of

the generic and specific features of the invention herein described, and all statements of the scope of the invention which, as a matter of language, might be said to fall therebetween.

Having described my invention, what I claim as new and desire to secure by Letters Patent, is:

1. In a dyeing apparatus, the combination with a winding mechanism, including a support upon which a running textile thread may be wound, of a dye jet mechanism mounted adjacent said thread for forcibly projecting a jet of dye upon the rapidly travelling thread to cause it to penetrate the fibers thereof, and means for causing relative movement between the jet and the thread transversely of the latter.

2. In a dyeing apparatus, the combination with a winding mechanism, including a support upon which a running textile thread may be wound, of a dye jet mechanism mounted adjacent said thread for forcibly projecting a jet of dye upon the rapidly travelling thread to cause it to penetrate the fibers thereof, and means for rendering said jet intermittent.

3. In a dyeing apparatus, the combination with a winding mechanism, including a support upon which a running textile thread may be wound, of a dye jet mechanism mounted adjacent said thread for forcibly projecting a jet of dye upon the rapidly travelling thread to cause it to penetrate the fibers thereof, a valve for said jet mechanism, and means for controlling said valve for regulating application of dye.

4. In a dyeing apparatus, the combination with a winding mechanism including a support on which a running textile thread is wound, of a dye jet mechanism mounted adjacent said support adapted to project a jet of dye upon said running textile thread, a valve for said jet mechanism and means controlled by said winding apparatus to operate said valve for rendering said dye jet intermittent.

5. In a dyeing apparatus, the combination with a winding mechanism including a support upon which a running textile thread is wound, of a dye jet mechanism mounted adjacent said support and adapted to project a jet of dye upon said running thread, and controlling means for said jet mechanism frictionally controlled by the thread when wound on said support.

6. In a dyeing apparatus, the combination with a winding mechanism including a support on which a running textile thread is wound at a variable rate, of a dye jet mechanism mounted adjacent said support and adapted to project a jet of dye upon said running thread, and means to control the jet mechanism to apply dye to the yarn proportionately to the rate of winding.

7. In a dyeing apparatus, the combination with a winding mechanism, including a support having a conical winding surface on which a running textile thread is wound at a variable rate, of a dye jet mechanism adapted to project a jet of dye upon said running thread, and control means for said jet mechanism frictionally engaging said conical surface to control application of dye proportionately to the rate of winding. 10
8. In a dyeing apparatus, the combination with a winding mechanism including a support upon which a running textile thread is wound, of a dye jet mechanism mounted adjacent said support and adapted to project a jet of dye upon said running thread, and means for terminating the application of dye upon interruption to the winding. 15
9. In a dyeing apparatus, the combination with a winding mechanism including a support on which a running textile thread is wound, of a dye jet mechanism mounted adjacent said support adapted to project a jet of dye upon said running thread, a valve for said jet mechanism, means for controlling said valve for regulating application of the dye, and means for automatically terminating control of said valve upon breaking the thread or decrease of tension thereof. 20
10. In a dyeing apparatus, the combination with a winding mechanism including a support on which a running textile thread is wound at a variable rate, of a dye jet mechanism mounted adjacent said support and adapted to project a jet of dye upon said running thread, means to control the jet mechanism to apply dye to the yarn proportionately to the rate of winding, and means for terminating application of dye upon interruption to the winding. 35
11. In a dyeing apparatus, the combination with a winding mechanism, including a support having a conical winding surface on which a running textile thread is wound at a variable rate, of a dye jet mechanism adapted to project a jet of dye upon said running thread, control means for said jet mechanism frictionally engaging said conical surface to control application of dye proportionately to the rate of winding, and means for terminating application of dye when the thread breaks or tension thereon is diminished. 45
12. In a dyeing apparatus, the combination with means for causing a thread to travel rapidly, of mechanism for projecting a jet of dye upon said rapidly travelling thread at a velocity whereby the dye is caused to penetrate the fibers thereof, and means frictionally driven by said rapidly travelling thread for rendering the dye jet intermittent. 55
13. In a dyeing apparatus, in combination, mechanism adapted to project a jet of dye upon a thread, means for establishing vari- 60
- able relative movement between said jet mechanism and thread, and automatically controlled mechanism for controlling said jet mechanism to apply dye thereby to the thread proportionately to said variable relative movement. 70
14. In a dyeing apparatus, in combination, mechanism adapted to project a jet of dye upon a thread, means for establishing variable relative movement between said jet mechanism and thread, an automatically controlled mechanism for controlling said jet mechanism to apply dye thereby to the thread proportionately to said variable relative movement, and automatic means for terminating application of the dye upon breaking of the thread or diminishing of the tension thereof. 75
15. In a dyeing apparatus, in combination, jet mechanism adapted to project a jet of dye upon a relatively moving thread, means for establishing relative movement between said jet mechanism and thread, and mechanism cooperating with said thread and dependent for operation upon said relative movement for controlling said jet mechanism and dye application thereby to the thread. 80
16. In a dyeing apparatus, in combination, jet mechanism adapted to project a jet of dye upon a relatively moving thread, means for establishing relative movement between said jet mechanism and thread, and means for controlling said jet mechanism to effect random application of dye to the thread proportionately to the rate of travel thereof. 95
17. In a dyeing apparatus, in combination with a winding mechanism including a support upon which a running textile thread is wound, of a dye jet mechanism mounted adjacent said support and adapted to project a jet of dye upon said running thread, and means controlled by said winding apparatus for rendering said jet intermittent, said means being normally held in operative position through tension of said running thread and automatically becoming inoperative upon interruption to said tension. 100
18. In a dyeing apparatus, the combination with a winding mechanism including a support upon which a running textile thread is wound, of a dye jet mechanism mounted adjacent said support and adapted to project a jet of dye upon said running thread, means for controlling said dye jet, and means for holding said jet mechanism in operative position controlled through tension of said running thread and rendering said jet mechanism inoperative upon interruption to 115
- thread tension. 120
19. In a dyeing apparatus, the combination with a winding mechanism including a support upon which a running textile thread is wound, of a dye jet mechanism mounted adjacent said support and adapted to project 130

a jet of dye upon said running thread, means for controlling said dye jet, and means for holding said jet mechanism in operative position controlled through tension of said running thread and rendering said jet mechanism inoperative upon interruption to thread tension, said last mentioned means including a plurality of cooperating power multiplying levers cooperating with said running thread.

20. In a dyeing apparatus, the combination with a winding mechanism including a support on which a running textile thread is wound, of a dye applicator mounted adjacent said support and controlled by said winding mechanism, a supporting abutment, a pair of connected levers adapted to contact with said abutment and connected with said applicator, and a lever acting as a guide 20 for the running yarn and cooperating with said first mentioned levers whereby yarn tension is employed to support said applicator in operative position.

21. In a dyeing apparatus, the combination with a winding mechanism including a support on which a running textile thread is wound, and a traveling guiding member for distributing the thread over the winding field of the support, of a dye applicator carried by said guiding member and controlled by said winding mechanism, an abutment post co-extensive with the travel of said guiding member, a lever connected with said applicator, a lever articulated to said first 35 mentioned lever and having its free end in position to contact with said post throughout the travel of said guiding member, and a yarn guiding lever cooperating with said first mentioned levers to hold said applicator in operative position.

22. In a dyeing apparatus, the combination with a winding mechanism including a bobbin, and means for winding a textile thread upon said bobbin and causing the 45 thread to travel at a high rate of speed, of a dye jet mechanism, mounted adjacent said rapidly travelling thread for projecting jets of dyes of different color thereon at a velocity whereby the dye is caused to penetrate the fibers of said thread.

23. In a dyeing apparatus, the combination with a winding mechanism including a support upon which a running textile thread is wound, of a dye jet mechanism mounted adjacent said support and adapted to project jets of dyes of different color upon said running thread, and means controlled by said winding apparatus for rendering said jets successively intermittent.

60 24. In a dyeing apparatus, the combination with a winding mechanism including a support on which a running textile thread is wound, of a jet mechanism mounted adjacent said support adapted to project jets of dyes of different color upon said running textile

thread, a valve for said jet mechanism provided with a plurality of jet ports, and means controlled by said winding apparatus to operate said valve for rendering the dye jets intermittent.

70

25. In a dyeing apparatus, the combination with a winding mechanism including a support on which a running textile thread is wound, of a jet mechanism mounted adjacent said support adapted to project jets of dyes of different color upon said thread, a valve for said jet mechanism provided with a plurality of jet ports, and means controlled by said winding apparatus to operate said valve for rendering said different colored dye jets successively intermittent.

80

26. In a dyeing apparatus, in combination, jet mechanism adapted to project dye jets upon a relatively moving thread, means for establishing relative movement between said jet mechanism and thread, means adapted to supply dyes from different sources to said jet mechanism, and means for controlling said jet mechanism to successively apply dyes from the different sources to the relatively moving thread.

85

27. In a dyeing apparatus, in combination, jet mechanism adapted to project a plurality of different dye jets upon a thread moving relatively to the jet mechanism at a variable rate, means for establishing variable relative movement between said jet mechanism and thread, and means for controlling said jet mechanism to apply the dye from the different jets to the thread proportionately to the rate of relative movement thereof.

90

28. In a dyeing apparatus, the combination with means for causing a textile thread to travel rapidly, of mechanism for projecting a jet of dye upon said rapidly travelling thread at a velocity whereby the dye is caused to penetrate the fibers of said thread, and means to control the flow of said jet proportionately to the rate of travel of the thread.

105

29. In a dyeing apparatus, the combination with a winding mechanism having a supporting frame, a winding bobbin on which a running textile thread is wound, and an oscillatable guiding member for guiding the running thread and carrying it over the winding surface of the bobbin, of a jet dye applicator carried by said guiding member and including a friction driven controlling member.

115

30. In a dyeing apparatus, the combination with a winding mechanism having a supporting frame, a winding bobbin on which a running textile thread is wound, and an oscillatable guiding member for guiding the running thread and carrying it over the winding surface of the bobbin, of a jet dye applicator carried by said guiding member, said dye applicator including a jet valve, a valve controlling member frictionally 125

130

- driven by the thread wound on said bobbin, and controlling connections between said valve and controlling member to effect intermittent random application of dye. 65
- 5 31. In a dyeing apparatus, the combination with a winding mechanism having a supporting frame, a winding bobbin on which a running textile thread is wound, and an oscillatable guiding member for guiding 10 the running thread and carrying it over the winding surface of the bobbin, of a dye applicator carried by said guiding member, and means for directly utilizing thread tension for holding said applicator in operative 15 position. 70
32. In a dyeing apparatus, the combination with a winding mechanism, having a supporting frame, a winding bobbin on which a running textile thread is wound, 20 and a swinging guiding frame oscillatable up and down for guiding the running thread and carrying it over the winding surface of the bobbin, of a dye applicator carried by said swinging frame and controlled by frictional engagement with the thread wound 25 on the bobbin, and means for directly utilizing thread tension for holding said applicator in operative position. 75
33. In a dyeing apparatus, the combination with a winding mechanism having a supporting frame, a winding bobbin on which a running textile thread is wound, and an oscillatable guiding member for guiding the running thread and carrying it 30 over the winding surface of the bobbin, of a dye applicator carried by said guiding member, and means for directly utilizing thread tension for holding said applicator in operative position, said last mentioned 35 means including an abutment post and an articulated lever construction operatively connected with said applicator and cooperating with said post. 80
34. In a dyeing apparatus, the combination with means for causing a textile thread to travel rapidly, of mechanism for projecting a jet of dye upon said rapidly travelling thread at a velocity whereby the dye is caused to penetrate the fibers of the thread, 40 and means frictionally driven by said travelling thread for controlling said jet mechanism. 85
35. A process for dyeing textiles which includes, causing rapid relative travelling movement between a textile thread and a dye jet, and forcibly projecting, during said relative movement, a concentrated jet of dye upon the textile thread so as to cause the dye to penetrate the fibres thereof. 90
- 60 36. A process for dyeing textiles which includes, forcibly projecting a jet of dye upon a rapidly travelling textile thread, causing it to penetrate the fibers thereof. 95
37. An improved process for dyeing textile threads, which includes winding thread on a support and simultaneously applying intermittent jet of dye to the traveling surface of the thread while in position on the support. 100
38. An improved process for dyeing textile threads, which includes winding thread on a support and at the same time applying successive intermittent jets of dyes of different color to the traveling surface of the thread while in position on the support. 105
39. A process for dyeing textile threads which includes, projecting a concentrated jet of dye upon a rapidly travelling thread. 110
40. A process for dyeing textiles which includes, forcibly projecting jets of dyes of different color upon a rapidly moving textile thread, causing the dyes to penetrate the fibers thereof. 115
41. A process for dyeing textiles which includes, projecting an intermittent jet of dye upon a rapidly running textile thread at a velocity whereby the dye is caused to penetrate the textile fibers, and regulating the application of dye proportionately to the rate of travel of the thread. 120
42. A process for dyeing textiles which includes, projecting a jet of dye upon a rapidly running textile thread at a velocity whereby the dye is caused to penetrate the textile fibers and regulating the application of dye proportionately to the rate of travel of the thread. 125
43. A process for dyeing textile thread which includes winding the thread upon a support and simultaneously moving a dye jet upon and transversely of the threads on the support. 130
44. A process for dyeing textile thread which includes projecting an intermittent jet of dye upon a thread so as to apply the dye thereto in intermittent patches, and varying the amount of dye applied per unit length of thread. 135
45. In a dyeing apparatus, in combination, mechanism adapted to project a jet of dye upon a thread travelling at a variable rate, and mechanism for controlling said jet mechanism so as to apply a less amount of dye per unit length of thread as the rate of thread travel increases. 140
46. In a dyeing apparatus, in combination, mechanism adapted to project a jet of dye upon a travelling thread, and mechanism to control said jet mechanism so as to initiate and terminate the jet abruptly, thereby to effect intermittent application of the dye jet to the thread. 145

In testimony whereof I affix my signature.

ROBERT GOULD JENNINGS.
